(45) **Date of Patent:** **Jun. 18, 1830**

---

(54) **IMPROVEMENT IN THE APPARATUS AND
PROCESS FOR MANUFACTURING OR
PREPARING SODA WATER**

(76) Inventor: **George Ott**

(The United States of America.)

TO ALL TO WHOM THESE Letters Patent SHALL COME:

Whereas George Ott, of ...
the United States hath alleged that he has invented a new and useful improvement
in the apparatus of process for manufacturing
preparing Soda Water.

which improvement he states has not been known or used before his application, hath
that he does really believe that he is the true inventor, or discoverer of the said improvement, hath
paid into the treasury of the United States the sum of thirty dollars, delivered a receipt for
the same, and presented a petition to the Secretary of State, signifying a desire of obtaining an
exclusive property in the said improvement, and praying that a patent may be granted for that
purpose. These are therefore to grant, according to law, to the said Geo. Ott
his heirs, administrators or assigns for the term of fourteen years from the eighteenth day of
June one thousand eight hundred and thirty ... the full and exclusive right and
liberty of making, constructing, using and vending to others to be used, the said improvement;
a description whereof is given in the words of the said Geo. Ott himself
in the schedule hereunto annexed, and is made a part of these presents.

In Testimony whereof, I have caused these Letters to be made Patent, and the
Seal of the United States to be hereunto affixed.

GIVEN under my hand, at the City of Washington, this eighteenth day
of June in the year of our Lord one thousand eight hundred
and thirty ... and of the independence of the United States of America
the fifty seventh.

BY THE PRESIDENT.

W.M. C. Wirt, Secretary of State.

City of Washington, To wit:

I DO HEREBY CERTIFY, That the foregoing Letters Patent were deli-
vered to me on the eighteenth day of June in the year of our
Lord one thousand eight hundred and thirty to be examined;
that I have examined the same and find them conformable to law; and
do hereby return the same to the Secretary of State, within fifteen days
from the date aforesaid, to wit, on this eighteenth day of June
in the year of our Lord.

Thos. Mayes, Esq., U.S. Attorney General, of the United States.

The United States of America.

TO ALL TO WHOM THESE Letters Patent SHALL COME.

Whereas George Ott, a citizen of

the United States, hath alleged that he has invented a new and useful improvement

in the apparatus of vessels for manufacturing
or preparing Soda Water
which improvement he states has not been known or used before his application, hath
paid into the treasury of the United States the sum of thirty dollars, delivered a receipt for
the same, and presented a petition to the Secretary of State, signifying a desire of obtaining an
exclusive property in the said improvement, and praying that a patent may be granted for that
purpose. These are therefore granted, according to law, to the said Geo. Ott
his heirs, administrators or assigns for the term of fourteen years from the eighteenth day of
June one thousand eight hundred and thirty. The full and exclusive right
of liberty of making, constructing, using and vending to others to be used, the said improvement,
a description whereof is given in the words of the said Geo. Ott
in the schedule hereunto and is made a part of these presents.

In Testimony whereof, I have caused these Letters to make a patent.

Given one thousand eight hundred and thirty . . . the first day of June, 1830, the liberty of making, constructing, using and vending to others to be used, the said improvement; a description whereof is given in the words of the said . . . Geo. W. . . himself, in the schedule hereunto annexed, and is made a part of these presents:

In Testimony whereof, I have caused these Letters to be made Patent, and the Seal of the United States to be hereunto affixed.

GIVEN under my hand, at the City of Washington, this eighteenth day of June, in the year of our Lord one thousand eight hundred and thirty, and of the independence of the United States of America the fifty-second.

BY THE PRESIDENT,

McCAULIFFE, Secretary of State.

City of Washington, To wit:
I DO HEREBY CERTIFY That the foregoing Letters Patent were delivered to me on the eighteenth day of June, in the year of our Lord one thousand eight hundred and thirty, to be examined; that I have examined the same, and find them conformable to law; and I do hereby return the same to the Secretary of State, within fifteen days from the date aforesaid, to wit, on the eighteenth day of June, in the year aforesaid.

Wm. M. Bassett, Attorney General of the United States.

The Schedule referred to in these Letters Patent, and making part of the same, containing a description in the words of the said George Ott himself, of his Improvement in the apparatus & process for manufacturing or preparing Soda Water.

To all whom it may concern, be it known that I, George Ott of Norfolk, in the County of Norfolk & State of Virginia, have invented certain useful improvements in the apparatus and process for manufacturing or preparing, the beverage usually denominated Soda Water, and that the following is a full and exact description of my said improvements.

In the apparatus, as usually constructed, the water & gas are contained in, and conducted through, vessels and pipes formed of brass or copper, the effect of which is not merely to communicate an unpleasant taste to the water, but to impregnate it with salts of copper, the whole of which are extremely deleterious. To obviate these objections and to render the apparatus more economical and efficient, are the objects which I claim to have accomplished. Instead of using brass or copper, I employ black tin, or an alloy thereof, in every case, excepting for the force pump. All the other parts, such as the condensers, pipes, coolers, brewing pipes, siphons & cistern, which are usually made of the former metal, I make of the latter, excepting in certain cases. I likewise altogether with a metallic cistern, and form one of wood, in constructing and containing it so to give it sufficient strength, and to render it completely impervious to air and water, under the insurance of pressure to which it is to be subjected.

The Schedule referred to in these Letters Patent, and making part of the same, containing a description in the words of the said George Ott himself, of his Improvement in the apparatus & process for manufacturing or preparing Soda Water.

To all whom it may concern, be it known that I, George Ott of Norfolk, in the County of Norfolk & State of Virginia, have invented certain useful improvements in the apparatus and process for manufacturing or preparing, the beverage usually denominated Soda Water, and that the following is a full and exact description of my said improvements.

13. *That the apparatus, as usually constructed, the water & gas are contained in, and conducted through, vessels and pipes formed of brass or copper, the effect of which is not merely to communicate an unpleasant taste to the water, but to impregnate it with salts of copper, the whole of which are extremely deleterious.* To obviate these objections and to render the apparatus more economical and efficient, are the objects which I claim to have accomplished. Instead of using brass, or copper, I employ black tin, or an alloy thereof, in every case, excepting for the force pump. All the other parts, such as the conductors, pipes, valves, branching pipes, various cisterns, which are usually made of the former, such as the cistern, and form one of wood, in constructing and casting it so to give it sufficient strength, and to render it impervious to air and water, under the immense pressure, to which it is subjected.

The Schedule referred to in these Letters Patent, and making part of the same, containing a description in the words of the said George Ott himself, of his Improvement in the apparatus & process for manufacturing or preparing Soda Water.

To all whom it may concern, be it known that I, George Ott of Norfolk, in the County of Norfolk & State of Virginia, have invented certain useful improvements in the apparatus and process for manufacturing or preparing, the beverage usually denominated Soda Water, and that the following is a full and exact description of my said improvements. In this apparatus, as usually constructed, the acting gas are contained in and conducted through vessels and passages formed of brass or copper, the effect of which is not merely to communicate an impervious tract to the water, but to impregnate it with cells of copper, the whole resulting

process for manufacturing or preparing, the beverage usually denominated Soda Water, and that the following is a full and exact description of my said improvements. In the apparatus, as usually constructed, the water & gas are contained in, and conducted through vessels and pipes, formed of brass or copper, the effect of which is not merely to communicate an unpleasant taste to the water, but to impregnate it with salts of copper, the whole of which are extremely deleterious. To obviate these objections and to render the apparatus more economical and efficient, are the objects which I claim to have accomplished. Instead of using brass, or copper, I employ, black tin, or an alloy thereof, in every case, excepting for the forcing pump. All the other parts, such as the conductors, pipes, coolers, branching pipes, screws & cistern, which are usually made of the former metal, I make of the latter, excepting in certain cases. I dispense altogether with a metallic cistern, and from one of wood, so constructing and setting it up to give it sufficient strength, and to render it completely impervious to air and water, under the influence of pressure to which it is to be subjected.

15. to give it greater strength, than brass, the screws, as well as some other parts, which are constructed thereof, have to be so formed, or made, as to correspond with the nature of the material of which they are made, and the doing this forms one part of my improvement.

In describing the particular form of certain parts, it is to be understood that it is not this, but the general principle and intention of such form, which I claim as my invention, as the same may admit of numerous modifications, still keeping the same object in view. In making my coupling boxes, I bore the two ends of the parts to be coupled together, as two tubes for example; one of the tubes is furnished with a flanch, and the other with a male screw; — I then insert the collar of leather between the two ends, and this being small, requires but little force to render it perfectly tight, which is effected by means of a box, made of block tin, in the usual form, but stronger than ordinary, as may be more clearly seen by the drawing deposited in the Patent Office. I sometimes unite two parts together, without cutting a screw upon either; in this case the junction is made by bringing the faces, or ends, of the two parts together, and uniting them by means of a iron cramp, passing under one section, and passing it from the other by a thumb screw, a washer being interposed between the points of junction. When cocks are required, I take those which are usually called brass cocks, enlarge the hole in the key, and line it with block tin; I also line the tubular parts of the cock, in the same manner, thus combining the strength of the original metal with the protecting quality of the tin. It is moreover that the copper or brass may be turned, and afterwards covered.

As the leather is lighter than brass, the screws, as well as some other parts, which are constructed thereof, have to be so formed, or modified, as to correspond with the nature of the material of which they are made, and the doing this forms one part of my improvement. In describing the particular form of certain parts, it is to be understood that it is not this, but the general principle and intention of such form, which I claim as my invention, as the same may admit of numerous modifications, still keeping the same object in view. In making my coupling boxes, I bring the two ends of the parts to be coupled together, as two tubes, for example; one of the tubes is furnished with a flange, and the other with a neck screw;—I then insert the collar of leather between the two ends, and this is secured by two leather bands, which are to be fastened by means of a box, made of black tan, or the usual pine, & so that these will never be more liable to injure the leather, than

parts to be coupled together, as two tubes for example; one of the tubes is furnished with a flange, and the other with a male screw;—I then insert the collar of leather between the two ends, and this being small requires but little force to render it perfectly tight, which is effected by means of a box, made of block tin in the usual form, but stouter than ordinary, as may be more clearly seen by the drawing deposited in the Patent Office. I sometimes unite two parts together, without cutting a screw upon either; in this case the junction is made by bringing the faces, or ends, of the two parts together; and uniting them by means of an iron cramp, I fix under one side, and pressing upon the other by a thumb-screw. A leather collar is placed between the points of junction. When works are required, I take those which are usually called brief works, whence the name in the key, and line it with block tin; I also line the tubular part of the cock in the same manner; thus combining the strength of the original metal with the protecting quality of the tin. It is important that the copper or brass may be turned, and a stem made.

covered with a thick coat of block tin, or an alloy thereof, by casting, and where extra strength may be required, I intend, sometimes, to do this; all the beneficial effects from the block tin being thus as well secured as though the whole was of that metal. When I construct my cisterns of metal, I make them of block tin, rolled out into sheets, properly formed, and united by soldering. These I insert in barrels of strong, seasoned wood, hinged closely with stout iron, and the heads secured by leaving three or four inches of the staves, at each end, projecting beyond the head; this space is to have a block of wood fitted into it, which should be so placed that its grain may cross that of the head, and it is to be secured by iron bolts. When the cistern of block tin is placed within the wooden vessel, cement is to be poured in between the two, so as completely to fill the space, and sustain the metal in every part.

I intend sometimes to melt the metal lining altogether, using only the wooden cistern, constructed as above. In this case, in order to render it water and air-tight, I line, and fill the pores on the inside with a suitable cement; for the purpose, I usually, combine together resin, beeswax and yellow ochre, or resin, bees-wax, pitch & ochre, using such portion of bees-wax as shall prevent its cracking, and such a quantity of ochre as shall give it hardness and consistency, the inside of the cistern, being perfectly dry, is heated, and the melted cement poured in; the vessel is then turned about and the superfluous portion allowed immediately to drain out. After a fair and full trial, I have found cisterns of this description to succeed perfectly. In preparing the Soda Water, when a portion of common air is mixed with the Carbonic Acid, it communicates an unpleasant, rapid taste to the water; to obviate this, in my *polybarometry*

covered with a thick coat of block tin, or an alloy thereof, by casting, and where extra strength may be required, I intend, sometimes, to do this; all the beneficial effects from the block tin being thus as well secured as through the whole mass of that metal. When I construct my bisters of metal, I make them of block tin, rolled out into sheets, properly formed, and united by soldering. These I insert in barrels of strong, seasoned wood, hopped closely with stout iron, and the heads secured by leaving three or four inches of the staves, at each end, projecting beyond the head; this space is to have a block of wood fitted into it, which should be so placed that its grain may cross that of the head, and it is to be secured by iron bolts. When the bottom of block tin is placed within the wooden vessel, cement is to be poured in between the two, so as completely to fill the space, and secure the metal in every part. I intend sometimes to omit the metal lining altogether, using only the wooden staves.

in certain pipes, cement is to be forced in between the two, so as to exclude all air-gapse, and make the tube ~~water~~ ^{air-tight} every part.

I intend sometimes to omit the metal lining altogether, using only the cork insulation, constructed as above. In this case, in order to render it ^{water}-tight, I inc, and fill the pores in the inside with a sub-
-stic cement; for the purpose, I usually, combine together resin, beeswax, and yellow ochre, or resin, beeswax, pitch of oche, resin and portion of beeswax as shall prevent its cracking, and such a quantity of ochre as shall give it hardness and consistency; the mass of the cusion, being perfectly dry, is heated, and the melted cement poured in, the vessel is then turned about and the superfluous portion allowed immediately to drain out. After a fair and full trial, I have found cusions of this description to succeed perfectly. In preparing the Soda Water, when a portion of common air is mixed with the Carbonic Acid, it communicates an unpleasant, sharp taste to the water; to obviate this, in my ^{polymerity}

properly, for use, for manufacturing it, as follows: I cover completely with water, and expel about one third of this water by carbonic acid.

To effect this, I make an opening in the side of the cistern, one third of its height below the top, which opening may be completely closed by means of a screw; leaving this open, I introduce the gas until the water is expelled, when I close it and proceed in the usual way.

What I claim, in the foregoing apparatus and in the mode of procedure, as my invention, is the manner in which I employ black tin, or an alloy of black tin, to conduct and retain the water and gas, of soda water, to prevent the deleterious effects experienced from other metals. I also claim the covering of brass, copper or other metal with black tin by fusing, or casting it thereon, so as to leave it in a body.

The expeller of gas from the cistern is composed of carbonic acid, in order that the water condensed may consist entirely thereof.
